UNITED STATES PATENT OFFICE.

ROBERT C. SPENCER, JR., OF RIVER FOREST, ILLINOIS.

MECHANISM FOR OPERATING CASEMENT WINDOWS, SHUTTERS, AND THE LIKE.

No. 808,486.

Specification of Letters Patent.

Patented Dec. 26, 1905.

Application filed April 24, 1905. Serial No. 257,122.

To all whom it may concern:

Be it known that I, ROBERT C. SPENCER, Jr., a citizen of the United States, and a resident of River Forest, in the county of Cook and State of Illinois, have invented an Improved Means or Mechanism for Operating Casement-Windows, Shutters, and the Like, of which the following is a specification.

This invention relates to means or mechanism for operating casement-windows, shutters, and the like and for securing them in adjusted position open or closed, and relates particularly to means or mechanism for this purpose of the type adapted for operation from within the room. A particular advantage of means or mechanism for operating casement-windows, shutters, and the like of this type is that where screens or other obstructions of a similar nature are secured in the window, opening necessarily inside of said window, raising or disturbing the adjustment of said screen or other obstruction is obviated. Also in rainy and stormy weather said window or shutters may be operated from within the room and without the person operating them being at all exposed.

The object of the invention is to provide means for operating casement-windows, shutters, and the like of the general type described which will be simple, strong, and durable and which may be readily applied to any window old or new.

To this end my improved means or mechanism for operating casement-windows and the like consists of the various features, combinations of features, and details of construction hereinafter described and claimed.

In the accompanying drawings, in which means or mechanism of my invention are fully illustrated, Figure 1 is a perspective view of part of a casement-window, together with my improved mechanism applied for operating the same. Fig. 2 is a sectional view thereof, showing my improved operating mechanism in top plan view. Fig. 3 is a sectional view, on an enlarged scale, of the handle or operating-lever of my improved operating mechanism; and Fig. 4 is a view substantially similar to Fig. 2, showing my improved operating mechanism applied to a window which opens inwardly.

For purposes of concrete illustration I have herein shown means or mechanism of my invention as applied for operating a casement-window.

Referring now to the drawings, A designates the sash of a casement-window; B, the stile of the window-frame; C, the stool of said window-frame; D, the apron thereof, and E a screen or the like secured in the window-frame inside of the sash to close the window-opening. All of the foregoing parts are old and well known in the art and may be of any desired or approved construction.

My improved means or mechanism for operating the window and for securing the same in adjusted position are as follows:

Mounted in a suitable rigid support, preferably the stool C of the window-frame, is a pivot-stud 1, which is preferably provided with a suitable bearing formed in a plate 2, secured to the stool C of the window-frame and having a boss or hub 3 on its under side which engages a suitable hole or opening in said stool C of the window-frame. The upper end of the pivot-stud 1 preferably extends some distance above the plate 2 and is provided with a shoulder which rests upon the top of said plate and operates to support said pivot-stud in desired position relatively to said plate. Rigidly secured in the upper end of the pivot-stud 1 is an arm 4, which projects laterally therefrom and is provided with a sliding connection to the window-sash A. In the preferable construction shown said arm 4 is tubular and is connected to the window-sash A by means of a rod 5, fitted to the bore of said arm 4, the outer end of which is pivoted to a bracket 6, secured to said window-sash A. The tubular rod A is made of such length that it will terminate short of the bracket 6 when said window is closed, and the rod 5 is of such length that when fully extended in the operation of the window a sufficient section thereof will remain in engagement with the bore of the arm 4 to form a rigid connection between said arm 4 and rod 5 to support said rod against lateral movement relatively to said arm 4. The pivot-stud 1 is preferably located closely adjacent to the hinged edge of the window A in the manner common in this type of operating mechanism. With this construction it is obvious that rotation of the pivot-stud 1 will impart movement to the window in one direction or the other, depending upon the direction in which said pivot-stud is turned.

Pivotal movement is adapted to be imparted to the pivot-stud 1 by means of an arm or rod 7, rigidly secured to the lower end

thereof and which projects below the boss or hub 3 on the bearing-plate 2 in such position that the outer end thereof will extend through a slot or opening 8, formed in the 5 window-apron D beyond the inner side of said window-apron. The slot or opening 8 is made sufficiently long to provide for necessary movement of the rod or arm 7 to fully open and close the window, and to provide 10 for assembling my improved operating mechanism the arm or rod 7 is removably secured to the pivot-stud 1, being preferably screw-threaded into a suitable hole or opening therein.

15 The window is adapted to be secured or locked in desired position in the following manner: Secured to the side of the window-apron D is a plate 9, in which is formed a slot 10, which registers with the slot 8 in said window-apron and through which the operating arm or rod 7 likewise extends. Formed in the sides of the slot 10 are notches 11, which are adapted to be engaged by a sleeve 12, fitted to the exterior of the arm or rod 7, so 20 as to be movable longitudinally thereof, thus providing for engagement and disengagement of said sleeve with said notches, as desired. In the preferable construction shown said sleeve is made tapering, the end thereof 25 adjacent to the pivot-stud 1 being slightly smaller than the notches 11 and the end thereof remote from said pivot-stud being slightly larger than said notches 11, thus providing for close engagement of said sleeve 30 with said notches to prevent all play or lost motion thereof. Movement of said sleeve 12 longitudinally of the arm or rod 7 is limited by means of a pin 13, secured in said sleeve, which engages a longitudinal slot 14 in said 35 arm or rod. In the preferable construction shown the sleeve 12 extends beyond the outer end of the arm or rod 7 and is provided with a ball or other hand-grip 15 on its outer end to provide for conveniently handling the 40 same.

45 It is obvious that my improved mechanism may be quickly applied to any window, whether old or new, as it simply involves attaching the plate 2 to the stool of the window, forming the slot or opening 8 in the apron 50 thereof, and attaching the locking-plate 9 to said apron D, with the opening 10 therein in register with the slot or opening 8 in said window-apron.

55 In Fig. 4 of the drawings I have shown my improved operating mechanism applied for operating a casement-window which opens inwardly. This application of my improved operating mechanism obviously involves no 60 departure from my invention, said operating mechanism comprising identically the same elements operating on identically the same principle, the only change involved being in the manner of attaching and applying the 65 same and in the relation of parts to secure

the necessary direction of movement of the sash, all of which will be readily understood from an inspection of said Fig. 4.

I claim as my invention—

1. The combination with a hinged member, of means for operating the same and for securing the same in adjusted position, comprising a rotatable stud, an arm secured therein, sliding connection between said arm and the hinged member, an operating lever or handle on said rotatable stud, a sleeve freely slideable longitudinally on said operating lever or handle and a fixed plate provided with a slot having edge notches adapted to receive the inner ends of said sleeve. 80

2. The combination with a hinge member, of means for operating the same and for securing the same in adjusted position, comprising a rotatable stud, an arm secured therein, sliding connection between said arm 85 and the hinged member, an operating lever or handle on said stud, a tapered sleeve longitudinally movable on said operating lever or handle, and a fixed plate provided with a slot provided with edge notches into which 90 the tapered portion of said sleeve is adapted to enter.

3. The combination with a hinged member, of means for operating the same and for securing the same in adjusted position, comprising a rotatable stud, an arm secured therein, sliding connection between said arm and said hinged member, an operating lever or handle on said stud, comprising a rod or arm secured in said stud and a tubular section longitudinally movable thereon and which forms the hand-grip of said lever or handle, and a fixed plate provided with notches adapted for engagement by said tubular section of said operating handle or lever, the 100 part of said tubular section designed for engagement with said notches being tapered. 105

4. The combination with a hinged member, of means for operating the same and for securing the same in adjusted position, comprising a rotatable stud, connection between said stud and said hinged member, comprising arms rigidly secured to said stud and pivoted to said hinged member, respectively, one of said arms being tubular and adapted 115 for telescopic engagement by the other, an operating lever or handle on said stud and means to secure said handle or lever in adjusted position. 110

5. The combination with a hinged member, of means for operating the same and for securing the same in adjusted position, comprising a rotatable stud, connection between said stud and said hinged member, comprising arms rigidly secured to said stud and pivoted to said hinged member, respectively, one of said arms being tubular and adapted 125 for telescopic engagement by the other, an operating lever or handle on said stud, a sleeve longitudinally movable on said oper- 130

ating lever or handle, and a fixed plate provided with notches adapted for engagement by said sleeve.

6. The combination with a hinged member, of means for operating the same and for securing the same in adjusted position, comprising a rotatable stud, connection between said stud and said hinged member, comprising arms rigidly secured to said stud and pivoted to said hinged member, respectively, one thereof being tubular and adapted for telescopic engagement by the other, an operating lever or handle on said stud, a tapered sleeve longitudinally movable on said operating lever or handle and a fixed plate provided with notches adapted for engagement by said sleeve.

7. The combination with a hinged member, of means for operating the same and for securing the same in adjusted position, comprising a rotatable stud, connection between said stud and said hinged member, comprising arms rigidly secured to said stud and pivoted to said hinged member, respectively, one thereof being tubular and adapted for telescopic engagement by the other, an operating lever or handle on said stud, comprising a rod or arm secured in said stud, and a tubular section longitudinally movable thereon which forms the hand-grip of said lever or handle, and a fixed plate provided with notches adapted for engagement by said tubular section of said operating handle or lever.

8. The combination with a window-frame and a member hinged thereto, of means for operating the hinged member and for locking the same in its adjusted positions, said

means comprising a rotatable stud carrying an arm having a sliding connection to said swinging member, an operating - lever on 40 said rotatable stud, a slotted plate through which said lever works, said plate being provided with a series of notches, and a handle slidable longitudinally on the said lever and adapted to engage said notches to lock the 45 lever against movement, said handle having a limited motion on the lever and projecting beyond its end to form an extension thereof.

9. The combination with a window-frame and a hinged member of means for operating the hinged member and locking it in its adjusted positions, said means comprising a rotatable stud journaled in the stool of the window-frame and depending below it, means connecting the upper end of this stud slidably with the swinging member, a lever or rod attached to the depending end of the stud and extending through a slot in the apron of the window-frame, a notched plate attached to said apron and provided with a 55 slot registering with the slot in the apron, the slot in this plate being provided with notches, and a part carried by the lever or rod and adapted to engage said notches to lock the device positively in its adjusted positions. 60 65

In testimony that I claim the foregoing as my invention I affix my signature, in presence of two subscribing witnesses, this 12th day of April, A. D. 1905.
